Application November 10, 1939, Serial No. 88,192

To all whom it may concern:

Be it known that I, John M. Foster, a citizen of the United States, residing at Marion, in the county of Grant and State of Indiana, have invented a new, original, and ornamental Design for a Bottle, of which the following is a specification, reference being had to the accompanying drawing, forming part thereof.

In the drawing, Fig. 1 is a front elevation of a bottle showing my new design. Fig. 2 is a fragmentary section through the shoulder por-

tion of the bottle; and Fig. 3 is a central vertical section through the shoulder portion of the bottle shown in Fig. 1.

The dominant feature of my design resides in the specific shoulder arranged in the particular manner shown and as emphasized by the full line disclosure of the bottle.

I claim:

The ornamental design for a bottle, as shown and described.

JOHN M. FOSTER.
